E. A. SANDLING,
ELECTRIC COIL BOX,
APPLICATION FILED JAN. 20, 1919.

1,419,691.

Patented June 13, 1922.

UNITED STATES PATENT OFFICE.

ELMER A. SANDLING, OF MOSS POINT, MISSISSIPPI.

ELECTRIC COIL BOX.

1,419,691.

Specification of Letters Patent. Patented June 13, 1922.

Application filed January 20, 1919. Serial No. 272,124.

To all whom it may concern:

Be it known that I, ELMER A. SANDLING, a citizen of the United States, residing at Moss Point, in the county of Jackson and 5 State of Mississippi, have invented certain new and useful Improvements in Electric Coil Boxes; and I do hereby declare the following to be a full, clear, and exact description of the invention, such as will enable 10 others skilled in the art to which it appertains to make and use the same.

This invention relates to certain new and useful improvements in a combined support and waterproof housing for use in connection 15 with an electric coil box.

In practice at the present time, great difficulty is experienced in adequately supporting and properly protecting the usual coil box of an ignition system from the absorption 20 of moisture. This is particularly true in the case of Ford automobiles, and also exposed coils in the ignition system of motorboats, where much trouble, delay, and expense is caused by the accumulation of 25 water and moisture about the coil and its terminal connections.

An object of the present invention is to overcome these difficulties, and produce an economical support of moisture-proof material 30 and construction, whereby the usual coils now employed can be similarly located in their relatively exposed positions without danger of short circuiting, reduction in the force or strength of the spark, and other 35 like trouble now experienced.

Another object of this invention is the production of a one-piece supporting shelf having integral terminal housings which can be quickly positioned against the usual front 40 or dashboard of an automobile.

A further object is to provide a readily attachable moisture-proof support to which the electrical connection can be easily secured and in such a manner as to render 45 them free from the collection or seepage of moisture.

With these and other objects in view, the invention further consists in the construction and arrangement of the several parts

hereinafter described and pointed out in the 50 appended claims.

In the accompanying drawings illustrating an embodiment of my invention,

Figure 1 is a sectional elevation illustrating the application of my improved support 55 and housing to an automobile of well known construction.

Figure 2 is a perspective view of the support and housing detached.

Figure 3 is a bottom plan view of the support and housing, and

Figure 4 is a detail sectional view through a portion of the support and housing at a point through which the terminal connection for the battery or magneto may pass. 65

The present invention has been primarily designed for use in connection with the coil box of the Ford automobile, but it will be understood that other exposed coil boxes can be retained therein. Many attempts 70 have been made as temporary expedients to prevent the wetting of the coil box and its connections, some of the most common being to protect the coil by moisture-proof coverings and water-shedding shields. These do 75 not prove satisfactory, for the seepage of the moisture and water down the windshield over the coil and down the dash or front board is not easily prevented by coverings.

The penetrating qualities of all moisture 80 and mist easily affect the wooden box, in which the coil is ordinarily supported, and readily enter the several joints in the wooden structure, at particularly the terminal connections. 85

The drying of the wooden box, or its cementing have many times been attempted, but the process causes much delay, inconvenience, and at the most is only temporary. 90

The herein described invention has been designed to overcome these difficulties and comprises a one-piece supporting shelf 1 having a supporting base 2, and a vertical wall 3 formed integral therewith from which 95 latter integral terminal housings or casings 4 extend. The material from which the one-piece shelf is made may be hard rubber,

porcelain, or other insulating and moisture-proof material, and I do not limit myself to the exact kind described.

The support as shown in Figure 1 is applied to the dash or front board 5 of a well known automobile, the terminal housings 4 extending through openings 6 formed in said front board 5. The usual cowl 7 and hood 8 of the automobile are fragmentally shown as illustrating the manner in which the water and moisture readily gravitate over the cowl and seep down the front dash board 5 into contact with the coil box.

The vertical wall 3 of the one-piece shelf 15 is recessed as indicated at 9, said recesses terminating short of the base portion 2. Into these recesses the electrical connections 10 and 11 of the respective high and low tension terminals are inserted. Each high tension connection 10 is formed on the end of the terminal 12, to the outer end of which latter is secured an electrical conductor leading to the spark plugs of the explosive engine. Each low tension connection 11 is formed on the end of the terminal 13 to the outer end of which latter is secured an electrical conductor leading to the commutator or timer of the engine.

The terminal housings or casings 4 completely encase the respective high and low tension terminals 12 and 13, and prevent the accumulation of water or moisture thereon.

Another series of electrical connections 14 are provided in a recessed portion 15 formed in the base portion 2 of the shelf 1. This recess 15 extends through to the respective ends of the base and receives a bar upon which the electrical connections 14 are provided.

40 The coils of the electrical system are adapted to be interposed between the electrical connections 10, 11 and 14 in the usual manner, and are preferably encased as indicated at 16 in Figure 1. The construction 45 of the coils and vibrator form no part of the present invention, and hence a further description thereof will not be given.

Extending through two of the terminal housings or casings 4, are battery and magneto terminals 17 and 18, respectively. These terminals are connected to the conductors 19 and 20, respectively, which in turn lead to the usual switch contained in the casing 21, as shown in Figure 1. These 55 conductors are adapted to snugly lie in grooves or ducts 22 formed in the one-piece shelf as shown. Another conductor, not shown, is also interposed in the groove 23 between the bar provided with the connections 14 and the switch. The base 2 of the shelf is cut away as at 24 to facilitate the outlet of the conductors 19 and 20 and their connection to the switch in a snug and compact manner.

The coils are further encased in a box-like structure 25, the body portion 26 of which is secured to and extends beneath the base portion 2 and is provided with a tongue or upturned edge 27 designed to spring into a groove 28 formed on the under side of said base portion 2. The upper portion or cover section 29 of the box-like structure engages the outside surface of the vertical wall 3 as shown in Figure 1, and is readily removable.

From the foregoing it will be obvious that practical advantages in construction are obtained whereby the water and moisture now admitted against the dash or front board of the automobile by its gravitation down the front of the machine, are excluded from contact with the coils and their respective electrical connections, thus ensuring steady operation of the ignition system, devoid of the trouble now experienced.

I claim:

1. A one-piece moisture-proof supporting shelf for electric coils comprising a supporting base and an integrally disposed vertical side wall, having a series of integral terminal housings extending therefrom.

2. A one-piece moisture-proof supporting shelf for electric coils, said shelf having vertical and horizontal portions provided with electrical connections against which the coils are positioned, a series of terminal housings 95 extending from the aforesaid vertical wall, and terminal connections extending from the aforesaid electrical connections and passing through said terminal housings.

3. A one-piece moisture-proof supporting shelf for electric coils, said shelf comprising a vertical wall provided with a series of spaced recesses, coil connections secured therein, a series of terminal housings extending from said vertical wall and having terminal connections therein, a supporting base extending from said vertical wall and formed integral therewith, a recess in said base and other coil connections positioned therein.

4. A one-piece moisture-proof supporting shelf for electrical coils, said shelf comprising a vertical wall provided with a series of spaced recesses, coil connections arranged in said recesses, a series of terminal housings 115 formed integral with said vertical wall, terminal connections secured therein, a supporting base formed integral with said wall, a recess formed in said supporting base, other coil connections secured therein, and a series 120 of ducts in said shelf adapted to receive electrical conductors.

5. A combined support and housing for electric coils comprising an angular shelf formed of a material impervious to water, 125 having terminal casings extending from one side of the said angular shelf, a box-like member secured to said shelf, and a cover

designed to engage the said shelf and box-like member.

6. A combined support and housing for electric coils comprising an integral, angular shelf formed of a material impervious to water, having terminal casings extending from one side of the said angular shelf, a box-like member secured to said shelf, a tongue on said box member, a groove provided in said shelf adapted to receive the

aforesaid tongue, and a cover designed to engage the upper edges of said shelf and box-like member.

In testimony whereof I affix my signature, in presence of two subscribing witnesses.

ELMER A. SANDLING.
